US0D1026376S

(12) **United States Design Patent** (10) **Patent No.:** **US D1,026,376 S**
(45) **Date of Patent:** **** May 7, 2024**

(54) **SINK DRAINER RACK**

(71) Applicant: **ATTOM TECH LLC**, Stafford, TX
(US)

(72) Inventors: **Xueyi Lu**, Shanghai (CN); **Yuru Zhang**, Shanghai (CN); **Haojun Wang**, Shanghai (CN)

(73) Assignee: **ATTOM TECH LLC**, Stafford, TX
(US)

(**) Term: **15 Years**

(21) Appl. No.: **29/925,727**

(22) Filed: **Jan. 25, 2024**

(51) **LOC (14) Cl.** **07-05**

(52) **U.S. Cl.**
USPC **D32/55**

(58) **Field of Classification Search**

USPC D32/35, 55-59
CPC A47J 47/16; A47J 47/20
See application file for complete search history.

(57) **CLAIM**

The ornamental design for a sink drainer rack, as shown and described.

DESCRIPTION

FIG. 1 is a front, top, and left perspective view of a sink drainer rack showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, bottom, and right perspective view thereof.

1 Claim, 8 Drawing Sheets
